UNITED STATES PATENT OFFICE.

HARRY I. THRALL, OF LITTLE FALLS, NEW YORK, ASSIGNOR TO
HOMER P. SNYDER MANUFACTURING COMPANY, OF LITTLE
FALLS, NEW YORK.

CIRCULAR-KNITTING MACHINE.

No. 824,759.

Specification of Letters Patent.

Patented July 3, 1906.

Application filed December 12, 1904. Serial No. 236,545.

To all whom it may concern:

Be it known that I, HARRY I. THRALL, a citizen of the United States, residing at Little Falls, in the county of Herkimer and State of New York, have invented certain new and useful Improvements in Circular-Knitting Machines; and I do hereby declare the following to be a full, clear, and exact description of the invention, such as will enable others skilled in the art to which it appertains to make and use the same.

My invention relates to circular-rib-knitting machines, and particularly to the dial and dial-cam cap; and it consists in a new construction and arrangement of cams, a new means of automatically controlling the movable cams, a new means for adjusting the dial and dial-cap, and in details of construction and arrangement.

The more important features of my invention are the construction of dial-cap with a central cap-hub, a series of segmental sections secured thereto and carrying on their lower surface the cams of which the main or projecting cams form a continuous ring of steel, so that the needle-butts come in contact only with the hard steel, corresponding series of steel cast-off or retracting cams and of guard-cams arranged one of each on each section, and a pivoted tucking-cam arranged in a cut-out in the projecting-cam and adapted to adjust the needles in plain-knitting or in the tuck position. A compound lever of peculiar construction is arranged on one of the yoke-studs, supported on the main gear-ring automatically to operate these movable cams and throw them from plain to tuck position, and vice versa. The primary lever of said compound lever is connected by a single connecting-rod to the cam-shifting ring, fitted to an annular groove in the cap, and said ring is connected to each tucking-cam by a strap.

The dial and cam-cap carried on the yoke by the shaft are leveled and centered in the yoke-ring by an adjusting-hub fitting loosely in the ring and provided with a series of clamping-screws for fixing it in adjusted position. The ring is provided with a series of screws on its lower surface, engaging with the hub-flange to level the parts, and with a series

of circumferential screws, engaging with the hub-periphery to center the parts.

In the drawings is represented a desirable embodiment of my invention, in which the reference characters of the specification indicate the corresponding parts in all the figures.

Figure I is an elevation of a machine made according to my invention. Fig. II is a top plan. Fig. III is an enlarged vertical section of a portion of the preceding to show the means for adjusting the hub. Fig. IV is an elevation of the head of the machine and adjacent parts, taken at a right angle to Fig. I. Fig. V is a horizontal section on line V-V of Fig. IV. Fig. VI is an inverted plan of a portion of the dial-cam plate. Figs. VII, VIII, and IX are views of the dial-cam-operating compound lever, respectively in vertical section and in plan, with the parts in different positions. Fig. X is a partial vertical section through the dial-cap hub and a section.

In the figures, 1 indicates the frame; 2, the bed-plate; 3, the top bed-plate; 4, the cylinder fixed thereto; 6, the main gear-ring, fitted to and rotating thereon; 8, the yoke-studs thereon, carrying the yoke 10 and the yoke-ring 11, provided with leveling-screws 13, inserted from below, and the peripheral centering-screws 14. The adjusting-hub A has the supporting-flange 16 resting on the ring and engaged by the leveling-screws and a tubular center 17 fitting loosely within the ring to leave sufficient clearance to center the parts by means of the centering-screws. The shaft 18 is fixed in the hub by set-screw 19. Heretofore various means have been proposed for centering the hub and the shaft, for such means were slow, difficult, and uncertain to operate. By my means the hub is first centered, the peripheral screws being set up sufficiently snug. The hub is then leveled, if necessary, all of which is easy for the ordinary mechanic. Finally the clamping-screws 15 are tightened, securing the hub in position. Evidently holes in flange 16 for said clamping-screws 15 must be large enough to permit adjustment.

21 is a hand-wheel fitted to short thread 100

on upper end of shaft 18 to raise the dial and cam-cap. The weight of the dial is supported on the shaft by collar 23, secured to lower end of shaft, as by set-screw 24.

5 30 is the cam-cap hub, secured on shaft by set-screw 31 and provided with annular groove 32 for cam-shift ring and with double offset 33 to receive the inner correspondingly-rabbeted edge of the sections 34, there secured, as by bolts 35. Each section carries one main or projecting cam 38, preferably provided with plain ends 39 39, which meet when the sections are assembled, forming a continuous hard-steel ring for engagement 10 with the needle-butts, so that the butts shall not come in contact with the cast-iron, which they heretofore tended to cut and wear. In smaller machines these plain ends are shortened or cut off entirely, the inclines on the 15 cams meeting. These main cams are provided with cut-outs 40, in which are pivoted the tuck-cams 41, adapted to be retracted to permit the needles to run in the tuck position and when projected to push the needles 20 into outer or cast-off position for plain-knitting position. Opposed to said main and pivoted cams are the cast-off or retracting cam 43 and the guard 44, one of each on each section, forming a substantially continuous 25 outer steel ring with spaces where desired on the periphery to withdraw injured needles and to insert new needles. Each tuck-cam is provided with a stud 46, extending up through slot 47 in the section and secured by screw 50 to outer end of its connecting-strap 51. These straps are adapted to be secured at their inner ends by screws 52 to cam-shift ring 53. The straps are also provided with section-screws 54, so that screws 30 35 40 45 50 may be removed and the strap and tuck-cam clamped in fixed position out of operation. Evidently a certain number of these tuck-cams must be operated in out or cast-off position, and the construction here shown 55 has been designed to permit the knitter to adjust the cams as desired to produce various combinations of tuck and plain knitting. As here shown the cams of an eight-feed machine are adjusted alternately to 60 tuck and to cast off.

The shift-cam ring 53 is connected by a connecting-rod 57 to the short end or extension of the primary lever 59, such connection being slightly adjustable by means of the 55 bolt 60 in slot 61. This primary lever is one element of a unitary compound lever of which all the parts are carried on a sleeve 63, adapted to be secured on one of the yoke-studs, whereby the lever is solidly supported 60 and not necessarily removed to repair or 65 adjust the other parts. On the sleeve is fixed intermediately the arm 65, carrying the fulcrum 66 of a link 67, connected at its outer end by a hole 68 and a stud 69 to the primary lever 59, swinging on the sleeve, and 65 at its inner end by a hole or notch 71 and a stud 72, playing in a slot 73 in said arm, to the secondary lever 74, also swinging on the sleeve. Both the holes in the ends of link 67 are elongated longitudinally to permit play. 70 In the under surface of said arm 65 are "spots" 76 or small sockets, with which engage a plug-ball 77, held up in a hole in the secondary lever by the flat spring 79, forming a spring-lock to hold said levers in position 75 so as not to be thrown out by jar and vibration. The collar 80 is a spacer between the parts. Evidently the two levers, holes, studs, position of link, &c., could be reversed. 80 These levers are operated to throw the tuck-cams in and out by means of a pattern-disk 82, carried on a stem 83, supported in bearing 84 and elevated by a chain-lever 85, operated by the usual pattern-chain 86, having medium links for tuck and high links for plain 85 knitting. A single high link is shown in Fig. IV. As here shown the pivoted cams are thrown into tuck position by engagement of the secondary lever with the disk 82 and are restored to plain-knitting position by engagement of the primary lever directly with said disk. The chain is operated by any usual 90 chain movement.

The machine is driven in the usual way from a pulley 88 by a pinion 89 engaging 95 with the rack on the main gear-ring.

B is the usual take-up mechanism, driven by a belt 90 on pulleys 91 92.

Having thus described my invention, what I claim as new, and desire to secure by Letters Patent, is—

1. In a knitting-machine, the combination with the yoke and yoke-ring suitably supported, of a shaft, the dial and cam cap supported on the shaft, a hub supported on the 105 ring, means to secure the shaft to the hub, peripheral screws in the ring to engage with the sides of the hub, and leveling-screws in the ring to engage with the under surface of the hub.
2. In a knitting-machine, the combination with the yoke, and yoke-ring and means to support said parts, of a flanged adjusting-hub supported on the ring, a shaft secured in the hub, the dial and dial-cam cap supported 115 on the shaft, and two series of adjusting-screws in the ring, one series adapted to engage with the sides of the hub, the other series to engage with the lower surface of the hub-flange.
3. In a knitting-machine, the combination with the top bed-plate, the main gear-ring supported thereon, yoke-studs on the main gear-ring, a yoke on the studs, a yoke-ring on the yoke centrally arranged on the yoke and 125 having a central opening and a flat upper

surface, an adjusting-hub having a flange resting on the yoke-ring surface and a tubular center of a smaller diameter than the ring-opening arranged in said opening, a series of leveling-screws inserted from below in the ring and adapted to engage with the lower surface of the flange a series of centering-screws arranged around the periphery of the ring and adapted to engage with the tubular center, a series of clamping-screws in the flange to engage with the ring, a vertical shaft arranged in the hub, a set-screw in the hub to engage with the shaft, and the dial and cam-cap supported on the lower end of the shaft.

4. In a knitting-machine, having the usual yoke and yoke-ring, means for adjusting the dial and the cam-cap, consisting of a hub supported on the ring, and leveling-screws in the ring to engage with the under surface of the hub, to level the hub and the parts connected thereto.

5. In a knitting-machine provided with the usual yoke and yoke-ring, means for adjusting the dial and the cam-cap, having in combination a hub supported on the ring, leveling-screws in the ring to engage with the under surface of the hub, and means to adjust the hub laterally.

30 6. In a knitting-machine, the combination with the yoke and yoke-ring suitably supported, of a shaft, the dial and the cam-cap supported on the shaft, a hub supported on the ring, means to secure the shaft to the hub, centering-screws in the ring to engage with the periphery of the hub, and leveling-screws in the ring to level the hub, said leveling-screws being arranged and operating substantially at right angles to the centering-screws.

40 7. In a circular-knitting machine, the combination with the vertical shaft and a suitable support therefor, of a cam-cap hub secured on the shaft and formed with a rabbeted margin and an inner annular groove, a cam-shift ring fitted to the groove, cam-sections fitted to the margin and secured on the hub, a steel projecting cam on each section, a steel tuck-cam pivotally supported in a cut-out in each 45 projecting-cam, a stub on each tuck-cam extending up through a slot in the section, a connecting-strap between each stud and the shift-ring, a steel retracting-cam and a steel guard-set opposite the projecting-cam on each section to form a continuous camway, and means to shift the shift-ring at predetermined times to shift the tuck-cams alternately out into cast-off position and back into tuck position, the adjacent ends of the 55 projecting-cams being substantially in contact and the retracting-cams and guards forming substantially a continuous outer ring with spaces for the withdrawal of needles.

8. In a compound lever for shifting the cams in a knitting-machine, the combination with a primary lever, and a second lever, said levers being journaled so as to be swung alternately to shift the cams, of a fixed arm and a link pivotally fulcrumed on said arm and pivotally connected to both levers, and an element adapted to come into engagement with one or the other of said arms at predetermined times, to swing the primary lever and shift the cam alternately into, and out of, operative position.

9. In a circular - knitting machine, the main gear-ring and yoke-studs thereon, and a compound cam-shifting lever arranged on one of the yoke-studs and having in combination a primary lever journaled in the stud, a secondary lever journaled on the stud, an arm fixed on the stud between the levers, a link pivotally supported near its center on the arm and having a pivotal connection at its ends respectively with the primary and secondary levers, a series of pivoted cams, connections between the primary lever and said cams, and means to engage alternately with the primary and secondary levers at predetermined intervals to swing the primary lever and shift the cams alternately in and out.

10. In a circular - knitting machine, the main gear-ring and yoke-studs thereon, and a compound cam-shifting lever arranged on one of the yoke-studs and having in combination a supporting-sleeve, a primary lever journaled on the sleeve, a secondary lever journaled on the sleeve, an arm fixed on the sleeve between the levers, a link pivotally supported at its center on the arm and having a pivotal connection at its ends respectively with the primary and the secondary levers, a series of pivoted cams, connections between the primary lever and said cams, and means to engage alternately with the primary and secondary levers at predetermined intervals to swing the primary lever and shift the cams alternately in and out.

11. In a circular - knitting machine, the main gear-ring and yoke, studs thereon, and a compound cam-shifting lever arranged on one of the yoke-studs and having in combination a supporting-sleeve, a primary lever journaled on the sleeve, said lever having a longer main end and an extension extending on the opposite side of the sleeve, a secondary lever journaled on the sleeve below the primary lever, an arm fixed on the sleeve between the levers, a link pivotally supported at its center on the arm and having a pivotal connection at its ends respectively with the primary and the secondary levers, a plug-ball in a hole in the secondary lever, a spring to hold said ball in engagement with sockets in the arm, a series of pivoted cams, a cam-shift

ring connected to said cams, a connection between the primary lever extension and said ring, and means to engage alternately with the primary and secondary levers at predetermined intervals to swing the primary lever and shift the cams alternately in and out.

12. In a compound lever for shifting the cams in a circular-knitting machine, the combination with a supporting-sleeve, of a primary lever and a secondary lever journaled

on the sleeve, and connections between said levers, whereby the primary lever is swung by the engagement of suitable means with the secondary lever.

In testimony whereof I affix my signature 15 in presence of two witnesses.

HARRY I. THRALL.
